UNITED STATES PATENT OFFICE.

LEE DE FOREST, OF NEW YORK, N. Y., ASSIGNOR TO GEORGE K. WOODWORTH, OF BOSTON, MASSACHUSETTS.

OSCILLATION-DETECTOR.

No. 867,878.

Specification of Letters Patent.

Patented Oct. 8, 1907.

Original application filed February 2, 1905, Serial No. 243,913. Divided and this application filed June 12, 1907.
Serial No. 378,504.

To all whom it may concern:

Be it known that I, LEE DE FOREST, a citizen of the United States, and a resident of New York, in the county of New York and State of New York, have invented a new and useful Improvement in Oscillation-Detectors, of which the following is a specification.

My invention relates to an improvement in the sensitive member used in systems of wireless telegraphy to detect the electrical waves or oscillations and comprises 10 the novel features hereinafter shown and described and particularly pointed out in the claims.

In the accompanying drawing, I have shown, and in the description thereof will point out, a certain form of construction and an arrangement of circuit which 15 may be employed in carrying out my invention, and in connection therewith I will point out the principle of my invention. It will be understood, however, that by no means all the known or possible embodiments of my invention are herein illustrated or described and 20 that the particular embodiment herein shown and described may be subjected to a wide range of variation without departing from the principle of my invention.

The drawing represents a space telegraph receiving system having connected therein one embodiment of 25 the oscillation responsive device which constitutes the subject matter of the present invention. It will be understood, however, that said oscillation responsive device and its local circuit may be connected in any suitable manner with a wireless telegraph receiving 30 system.

In the figure, A represents an antenna or receiving conductor, or wave intercepting means; E represents the earth connection, D represents a Bunsen burner; T is a receiving or indicating instrument which is 35 herein shown as a telephone receiver, the same being shown only as typical of any form of signal indicating device capable of being employed.

I have discovered that if two electrodes or conductive members be separated, the separation between them may be neutralized sufficiently to enable them to act as a detector of electrical oscillations, if the intervening gaseous medium which separates said electrodes be maintained in a condition of intense molecular and 40 ionic activity, such for instance as would be caused by heating said gaseous medium in any suitable manner. This principle is embodied in the apparatus illustrated in the drawing. Obviously the electrode F³, which is placed as shown in the flame of the Bunsen burner, is maintained at a high temperature 45 relative to the lip of the burner which is of relatively low temperature. Thus there is formed a local receiving circuit possessing a certain asymmetric

electrical conductivity, whereby the current from the battery B, if used, will flow more readily from the relatively cool burner D to the more highly heated 55 electrode F³, this local circuit comprising the burner D, telephone or other signal indicating device T, electrode F³, that portion of the flame intervening between the electrode F³ and the burner D, and the battery B, if employed. In this case the burner itself 60 forms one of the two electrodes or conductive members above referred to as separated by a gaseous medium maintained in a condition of intense molecular and ionic activity.

Although I have shown a Bunsen burner for the purpose of maintaining the gaseous medium intervening between the electrodes D and F³ in a condition of intense molecular activity by the combustion of gases intervening between said electrodes, it will be understood that I do not limit myself to this particular heating device, which is not essential, as any means of heating may be employed.

The influence of the electrical oscillations developed in the oscillation circuit A—E produces current variations in the aforesaid local circuit, thus affecting the 75 indicating instrument therein to produce a signal. This may be due to ionization of the gas intervening between the electrodes, which greatly increases the conductivity of said gas, said ionization being accomplished in the present instance by putting said 80 gas into a condition of intense molecular activity.

This application is a division of my application Serial No. 243,913, filed Feb. 2, 1905, and the figure of the drawing accompanying the present application is identical with Fig. 4 of the patent application. 85

I claim:

1. An oscillation responsive device comprising a Bunsen burner, an electrode placed in the flame thereof, a local circuit connecting said burner and electrode, a signal indicating device and a source of electromotive force connected in said local circuit, and means whereby the oscillations to be detected may be impressed upon said flame. 90

2. An oscillation responsive device comprising a gaseous medium maintained in a condition of molecular and ionic activity, two electrodes associated with said gaseous medium, one of said electrodes being maintained at a high temperature and the other at a relatively lower temperature, a local circuit connecting said electrodes, a source of electromotive force and a signal indicating device connected in said local circuit, and means whereby the oscillations to be detected may be impressed upon said gaseous medium. 95

3. An oscillation responsive device comprising a gaseous medium maintained in a condition of molecular and ionic activity, two electrodes associated with said gaseous medium, one of said electrodes being maintained at a high temperature and the other at a relatively lower temperature, a local circuit connecting said electrodes, a source of 100

- electromotive force included in said local circuit, a signal-indicating device operatively connected with said local circuit, and means whereby the oscillations to be detected may be impressed upon said gaseous medium.
5. An oscillation responsive device comprising a gaseous medium maintained in a condition of molecular and ionic activity, two electrodes associated with said gaseous medium, one of said electrodes being maintained at a high temperature and the other at a relatively lower temperature, means whereby the oscillations to be detected may be impressed upon said gaseous medium, and means operatively connected therewith and responsive to alterations in the conductivity thereof.
10. An oscillation responsive device comprising a gaseous medium maintained in a condition of molecular and ionic activity, two electrodes associated with said gaseous medium, one of said electrodes being maintained at a relatively high temperature with respect to the other, means whereby the electrical oscillations to be detected may be impressed upon said gaseous medium, a local circuit connecting said electrodes and a signal indicating device operatively associated with said local circuit.
15. A wireless-telegraph local-receiving-circuit having a portion of its length formed of a gaseous medium maintained in a condition of intense molecular and ionic activity and possessing an asymmetric electrical conductivity, a signal indicating device operatively associated with said local circuit and means whereby the oscillations to be detected may be impressed upon said gaseous medium.

Correction in Letters Patent No. 867,878.

It is hereby certified that in Letters Patent No. 867,878, granted October 8, 1907, upon the application of Lee de Forest, of New York, N. Y., for an improvement in "Oscillation-Detectors," an error appears in the printed specification requiring correction, as follows: In line 85, page 1, the word "patent" should read *parent*; and that the said Letters Patent should be read with this correction therein that the same may conform to the record of the case in the Patent Office.

Signed and sealed this 29th day of October, A. D., 1907.

[SEAL.]

E. B. MOORE,
Commissioner of Patents.
